UNITED STATES PATENT OFFICE.

GEORGE D. HILL, OF LOUISVILLE, KENTUCKY.

RAIL-FASTENING.

1,028,878.

Specification of Letters Patent. Patented June 11, 1912.

Application filed August 17, 1911. Serial No. 644,678.

To all whom it may concern:

Be it known that I, GEORGE D. HILL, a citizen of the United States, and a resident of Louisville, in the county of Jefferson and 5 State of Kentucky, have invented new and useful Improvements in Rail-Fastenings for Use with Reinforced Railway-Ties, of which the following is a specification.

My invention has reference to reinforced 10 composite railway ties, having new, improved and effective means provided for fastening and retaining the railway rail to the reinforcement in said improved reinforced tie, and consists of a body of any desired 15 form or shape having embedded therein twisted metal reinforcement of the shape and style shown by the accompanying drawing, to strengthen and reinforce the concrete or other suitable plastic material, by which 20 this reinforcement must be surrounded in reinforced railway ties of this class, together with new and novel holding devices for the rail fastening.

My invention further provides economical, 25 new and improved means of supporting the metal reinforcement in a collapsible metallic casting-box form, and holding same in proper position while being surrounded by the concrete or other suitable plastic material 30 forming part of the reinforced railway tie when completed for use.

My invention further relates to reinforced railway ties having new, novel and effective means of rail fastening devices, having such 35 a fastening plate for fastening and retaining the railway rails to said reinforcement in said improved reinforced railway tie, by means of the novel features hereinafter more fully described, that will allow for longitudinal 40 expansion and contraction of the rail, and also allow for the gage of the railway rails being fastened to the reinforced railway tie, to be widened when necessary.

The invention will be best understood 45 by consideration of the following detail description taken in connection with the accompanying drawing, forming a part of this specification, in which drawing—

Figure 1 is a longitudinal half vertical 50 sectional view of a reinforced railway tie, reinforced in any desirable manner. Fig. 2 is a half plan top view of the rail fastening and its reinforcement, showing a rail in place in said fastening, and a fastening plate, 55 having clips attached to the flange of the rail ready to be driven into place.

In both Figs. 1 and 2, there is shown only a half view of my invention, since the half shown is a duplicate of the other half; a delineation of the one section or half part will suffice for that of the other. Fig. 3 is a longitudinal vertical sectional view showing the method and means of fastening and supporting the rail. Fig. 4 is a perspective view of the fastening plate. Fig. 5 is a transverse 60 cross section of a type of insulated connection joining together the duplicate parts of the reinforcement, showing the two halves of the reinforcement electrically insulated from each other. Fig. 6 is a perspective 65 view of a metallic collapsible form showing one side and one end collapsed.

Referring to the figures by characters of reference, in which similar characters refer to similar parts throughout the several views, 70 the metal reinforcing members 6 consist of four twisted rods fastened to the rail fastening devices, and positioned so as to resist tensile stresses, being embedded in concrete or other suitable plastic material, 75 as shown in Fig. 1.

6 is the reinforcement with a rail 2 in place in rail fastening 3 with fastening plate 4 having its clips 14 and 15 attached to the flange of the rail 2 ready to be driven 80 into place, as shown in Fig. 2.

For economy of manufacturing the reinforcement in the reinforced railway tie 6, the metallic reinforcement is made in duplicate parts so that the four twisted metallic 90 longitudinal rods 6, forming part of the reinforcement, may be joined on to corresponding ends of the duplicate part by means of metallic joints 7, which may be made in any suitable way. 95

2 is a rail in place. 3 represents shoulders formed in the flanged shape shown, and fastened to the reinforcement 6 by means of rivets 13 in such a way as to easily admit the flanges of the rail 2 between the inside faces of these shoulders 3 and at the same time allowing the metal fastening plate 4 to be applied to the flanges of the rail 2 and the said fastening plate 4 to be driven so as to be interposed 105 in the space between the inside faces of the shoulders 3 and the flanges of the rail 2. The fastening plate 4 has clips 14 and 15 bent to fit the flanges of the rail 2, these clips 110 14 and 15 being located at two opposite diagonal corners of plate 4. (See Fig. 4.) The outside edges of clips 14 and 15 when

the plate 4 is driven into final position for fastening the rail to the reinforced railway tie, that is, between the shoulders 3 of the fastening device, fit into corresponding recesses in the inside faces of shoulders 3, so that these recesses will prevent the fastening plate from being easily removed or slipped out from between the shoulders 3, thereby holding rail 2 in a fixed position upon the reinforced railway tie, but allowing for longitudinal expansion and contraction of the rail. If desired as an additional means of reducing to a minimum the jar to which plate 4 will be subjected, by reason of the weight or pounding effect of a vehicle passing over rail 2 which is fastened to the reinforced railway tie by means of the plate 4, thus tending to loosen the fastening plate 4 from between the shoulders 3, a metallic box 16 may be provided (which may be filled with asphalt or other suitable material), said metallic box 16 being fastened to the reinforcement 6 by rivets or bolts 13 underneath the fastening device.

Clips 14 and 15 are located at two opposite diagonal corners of the fastening plate 4, it being so formed that one of these clips 14 and 15 is thicker than the other, so that when rail 2, Fig. 3, is placed between the shoulders 3, for the reception of the fastening plate 4, and the fastening plate 4 is driven along the flanges of the rail 2, into its final position, as shown between the shoulders 3, the longitudinal center line of the rail may be to the one side or the other of the longitudinal center line of outside plate 4 by reason of the said clips 14 and 15 being of different thicknesses. This permits the rail to be thrown slightly to one side or to the other of the center line between the shoulders 3, depending upon which way the plate is driven between the shoulders 3. Thus, if 15 be the thin clip, and 14 the thick clip of the fastening plate 4, the rail will be thrown nearer the shoulder of the thin clip 15 than it is to the shoulder of the thick clip 14. When both thin clips—of the plate 4 of the fastening plates, under each rail of this fastening device, in this class of reinforced railway ties—are toward the center line of the two rails so fastened by the fastening plate 4, the gage of the track is standard; when both thick clips of the two fastening plates holding each of the two rails in the fastening herein described are toward the center line of the railway track, the rails are at maximum gage distance apart, necessary for curves. This variation, between the gage of the maximum and standard, is regulated by a graded variety of fastening plates of the general shape shown in 4 with the thickness of clip 14 over that of clip 15 so regulated that it will give the desired gage between the rails. I do not, however, confine myself to this method alone of ad-

justing for the variation of gage of rails on curves when the reinforced railway tie of this class, with the rail fastening device herein described, is used. The bolt holes in joint may be fitted with eccentric bushings 70 for the purpose of substantially varying the gage. (See Fig. 5.)

8 is any insulating material placed between the metallic parts of joint 7 and the reinforcement 6.

10 is a bolt of this joint.

The side 18 and the end 19 of the metallic casting-box form, in Fig. 6, are collapsed, with side 17 standing in a vertical position with reference to its base. The side 17 has 80 vertical slots 20 near each end, and at the proper distance apart for the reception of the shoulders 3 of the rail fastening device, after the duplicate parts of the reinforcement 6 shall have been fastened together by 85 the joint 7, Fig. 2. These slots 20, in the side 17 of the metallic casting-box form, thus suspend—without any additional support or contrivances for holding same in position—the metal reinforcement in reinforced railway ties of this class, so that the collapsible ends, 19 and 19, and the other side 18 of this metallic casting-box form, may be moved on their hinges so as to form a receptacle for the retention of the concrete 95 or other plastic material in which the reinforcement must be embedded to form the body of the railway tie. By reason of the sides 17 and 18, and the ends 19 and 19, being so fastened to the bottom of this metallic 100 casting-box form by means of suitable hinges, with locking pins 21, which may be removed, allowing the side 18, and ends 19 and 19, to be collapsed from around the concrete or other suitable plastic material forming 105 the body of the reinforced tie of this sort, the whole tie may be removed from the metallic casting-box form, by simply raising the shoulders 3 of the fastening devices from off the slots 20, that is, after the concrete or 110 other suitable plastic material shall have become sufficiently set.

Having fully described my invention, what I claim as new and desire to secure by Letters Patent, is:—

1. A reinforced concrete railway tie, having a rail fastening fastened thereon comprising two flange shaped shoulders for the reception and retention of the rails, with a locking plate fitting therein, substantially as described and set forth.

2. A reinforced railway tie consisting of a body of concrete, or suitable plastic material, wherein is embedded twisted shaped metallic longitudinal reinforcements, with 120 rail fastening devices, each of said rail fastening devices consisting of two flange shaped shoulders fastened to the reinforcement, embedded in the concrete or other suitable plastic material forming the body 130

of said tie, having recesses in the inside faces for the retention in place of a rail fastening plate, substantially as described and set forth.

5 3. A reinforced railway tie consisting of a body of concrete or suitable plastic material wherein is embedded twisted shape metallic longitudinal reinforcements, with rail fastening devices attached thereto, each 10 of said rail fastening devices consisting of two flanged shoulders fastened to the reinforcement, embedded in the concrete, or other suitable plastic material, forming the body of said reinforced railway tie, adapted 15 to receive and retain a metallic locking plate with fastening clips of unequal thickness on opposite diagonal corners, for widening the gage of rails to the extent necessary to suit the degree of curvature, substantially as de- 20 scribed and set forth.

4. A twisted shape metallic longitudinal reinforcement with rail fastening devices attached thereto, each of said rail fastening devices consisting of two flange shaped 25 shoulders, fastened to the reinforcement, in combination with a suitable metallic casting-box having slots in its sides in which the said shoulders are adapted to fit, for suspending in proper position the metallic 30 reinforcement, while being surrounded by the concrete or other suitable plastic material, substantially as described and set forth.

35 5. A metallic railway fastening device with reversible gage adjusting fastening

plate fitting therein, in combination with a reinforced concrete railway tie and rail mounted thereon and the metallic reinforcement embedded therein, substantially as de- 40 scribed.

6. A reinforced railway tie, consisting of a body of concrete or other suitable plastic material, wherein are embedded twisted shape metallic longitudinal reinforcement with rail fastening devices attached thereto, each of said rail fastening devices consisting of two flange shaped shoulders fastened to the reinforcement embedded in the concrete or other plastic material forming the body of said reinforced railway tie, hav- 45 ing directly underneath a metallic box filled with asphalt, and attached to the reinforcement by rivets or bolts and being embedded in the concrete or other plastic material si- 50 multaneously with the reinforcement in said reinforced railway tie, each of these metallic boxes being filled with asphalt acting as a cushion for the rails resting in the rail fastening devices and for keeping the locking plate in said rail fastening devices from 55 working loose, by reason of any jar to which they may be subjected, substantially as described and set forth.

In testimony that I claim the foregoing as my own, I have hereto affixed my signature 60 in the presence of two witnesses.
